UNITED STATES PATENT OFFICE.

HARRY R. GOGAY, OF COLUMBUS, OHIO, ASSIGNOR TO THE SOLAR METAL PRODUCTS COMPANY, OF COLUMBUS, OHIO, A CORPORATION OF NEW YORK.

METAL DOOR AND WINDOW CONSTRUCTION.

1,287,673.

Specification of Letters Patent.

Patented Dec. 17, 1918.

Application filed February 26, 1917. Serial No. 150,958.

To all whom it may concern:

Be it known that I, HARRY R. GOGAY, a citizen of the United States, residing at Columbus, in the county of Franklin and State 5 of Ohio, have invented certain new and useful Improvements in Metal Door and Window Constructions, of which the following is a specification.

This invention relates to metal door and 10 window construction designed to be placed in a wall opening. Specifically, this invention relates to a means whereby the jambs may be properly spaced apart and securely held in such position, both during the erecting 15 period and after the same has been completely installed.

To this end, my invention consists essentially of a spreader structure in combination with the jambs of such type that the jamb 20 structure may be adjusted as to height to obtain the proper door opening and also be securely held in position both during the time of application and afterward.

The novel features of this invention will 25 appear from the accompanying detailed description of the accompanying sheet of drawings in which similar characters of reference designate corresponding parts, and in which:

30 Figure 1 is a view in side elevation, showing a door frame in its finished state,

Fig. 2 is an enlarged vertical section taken 35 through the lower portion of this door frame, showing the manner in which it is anchored in position by the use of my invention,

Fig. 3 is an enlarged sectional view taken on line 3—3 of Fig. 1, and,

Fig. 4 is a fragmentary view in perspective 40 showing my improved type of spreader element.

In these figures, my invention is shown as being used in connection with a door structure in which the numeral 1 designates the jamb. In the present structure the trim 2 is

45 shown as forming an integral portion of the jamb but, it will be understood that this trim may be either integrally formed or separately formed, as may be desired. In the manufacture of these frames, it is essential

50 that the jamb should be somewhat higher than the desired door opening 3 and this is shown particularly clear in Fig. 2 in which the reference numeral 4 designates the sub-floor or main floor support of any desired 55 character and the numeral 5 designates the

surface floor specifically. In this figure, the jambs 1 are shown as projecting beneath the finished surface of the floor 5 and also that the U-shaped spreader element 6 is securely anchored in position to the sub-floor 4 by 60 means of the bolts shown at 7. The two upstanding legs 8 of this U-shaped spreader element are provided with a double row of apertures 9 spaced vertically from each other as is shown. The lower, end of each leg of 65 the jamb is provided with a pair of apertures designed to register with any horizontal pair of apertures 9. When the proper door opening has been determined, the jambs are set in position and the bolts 10 made to 70 pass through the registering apertures to securely fasten them in their proper position of adjustment. It will be noted that these apertures are located below the finished floor level so that the bolts are all hidden from 75 view and also that the upstanding legs 8 are located on the inside face of each of the jambs, so that after the structure has been assembled, this spreader and anchoring means is permanently hidden from view. 80 The spreader is also preferably reinforced or stiffened as, for instance, by the channel element shown.

What I claim, is:

1. The combination with a jamb longer 85 than a desired wall opening and having the lower extremities thereof apertured and terminating beneath the floor level, of a spreader and jamb supporting structure including the pair of vertically disposed leg 90 members operable to extend co-adjacent to the lower extremities of said jamb and having a plurality of vertically spaced apertures formed therein, and fastening elements passing through the apertures in said jamb extremities and through selected apertures formed in said leg members to adjustably yet rigidly secure said jamb to said spreader structure.

2. The combination with a jamb of greater 100 length than a desired wall opening whereby the lower extremities thereof terminate beneath the floor level, of a spreader and jamb supporting structure rigidly maintained in a fixed position beneath said floor level, upright members carried by said spreader structure and situated adjacent to said jamb extremities, and binding elements passing through vertically alined apertures formed in said upright members and jamb extremi- 110

ties to adjustably secure said jamb to said spreader structure.

3. The combination with a U-shaped jamb formed to embrace the walls of a door opening, the free extremities of said jamb terminating beneath the floor level of said opening, means for supporting said jamb in its applied position within said opening, comprising a base member rigidly anchored beneath the floor level, and means for adjustably connecting the free extremities of said jamb with said base member.

4. The combination with a jamb formed to be longer than a desired wall opening and

having the lower extremities thereof apertured and terminating beneath the floor level, of a base member securely anchored beneath said floor level, and means formed with said base member to effect the support of said jamb and to permit of its vertical adjustment.

In testimony whereof I affix my signature in presence of two witnesses.

HARRY R. GOGAY.
